DESIGN FOR A NURSING BOTTLE HOLDER

Edgar G. Beckemeyer, Columbus, Ohio

Application January 22, 1945, Serial No. 117,550

Term of patent 14 years

(Cl. D83—8)

To all whom it may concern:

Be it known that I, Edgar G. Beckemeyer, a citizen of the United States and a resident of Columbus, in the county of Franklin and State of Ohio, have invented a new, original, and ornamental Design for a Nursing Bottle Holder, of which the following is a specification, reference being had to the accompanying drawing which forms a part hereof.

In the drawing:

Fig. 1 is a front perspective view of a nursing bottle holder showing my new design; and
Fig. 2 is a top plan view thereof.

I claim:

The ornamental design for a nursing bottle holder, substantially as shown.

EDGAR G. BECKEMEYER.
